CIGAR LIGHTER

Oscar Fairless, Idaho Falls, Idaho

Application June 6, 1935, Serial No. 25,292

2 Claims. (Cl. 175—296)

The present invention relates to new and useful improvements in cigar lighters and has for its primary object to provide, in a manner as herein-after set forth, a device of this character which 5 will automatically light when lifted from the supporting surface upon which it may be resting.

Another very important object of the invention is to provide a cigar lighter of the aforementioned character which will automatically be extinguished when it is placed on a supporting surface.

Other objects of the invention are to provide a cigar lighter of the character described which will be comparatively simple in construction, 15 strong, durable, highly efficient and reliable in use, compact, light in weight, attractive in appearance and which may be manufactured at low cost.

All of the foregoing and still further objects 20 and advantages of the invention will become apparent from a study of the following specification, taken in connection with the accompanying drawings wherein like characters of reference designate corresponding parts throughout the several 25 views, and wherein:—

Figure 1 is an elevational view of a cigar lighter constructed in accordance with the present invention.

Figure 2 is a view in top plan of the device.

Figure 3 is a vertical sectional view, taken substantially on the line 3—3 of Figure 2.

Figure 4 is a vertical sectional view, taken substantially on the line 4—4 of Figure 3.

Figure 5 is a detail view in plan of the switch 35 closing member.

Figure 6 is a detail view in vertical section, taken substantially on the line 6—6 of Figure 3.

Referring now to the drawings in detail, it will be seen that the embodiment of the invention 40 which has been illustrated comprises a substantially conical casing 1 of suitable material from the top of which a substantially cylindrical neck 2 rises. The neck 2 is closed at its upper end, as at 3. The reference numeral 4 designates the bottom of the casing 1.

Mounted in the neck portion 2 of the casing 1 is a container 5 for the reception of a liquid fuel. A neck 6 projects upwardly from the container 5 through the top 3 of the casing 1 and mounted 50 in said neck 6 is a wick 7 which extends downwardly into the fuel in the container 5.

Mounted in the casing 1 is a coil 8 which is electrically connected to the container 5 as by a conductor wire 9. It may be well to here state 55 that the container 5 is of current conducting ma-

terial. Closely associated with the upper end of the container neck 6 is an electrode 10 which extends downwardly into the casing 1 and is connected with the coil 8 by a conductor wire 11. This is illustrated to advantage in Figure 3 of 5 the drawings.

Mounted for vertical reciprocation in a guide 12 in the casing 1 is a plunger 13 which extends slidably through the bottom 4 of said casing 1 and has secured on its lower end a rubber foot 14. 10 The opening provided in the casing bottom 4 for the plunger 13 is substantially conical and the foot 14 is correspondingly shaped for engagement in said opening. An opening 15 is provided in the top portion of the neck 2 and operable therein 15 is an extinguisher 16 which is mounted for swinging movement in a vertical plane. The extinguisher 16 includes a substantially concavo-convex head 17 on its free end which is engageable with the upper end of the wick 7 for extinguishing the flame. A link 18 connects the extinguisher 16 to the plunger 13 for actuation thereby.

The reference numeral 19 designates conductor wires to the coil 8 from a suitable source of current supply. Interposed in the line to the coil 8 is a 25 switch designated generally by the reference numeral 20. The switch 20 comprises a pair of normally spaced resilient contacts 21 which are mounted on the guide 12. Adjustably mounted on the upper end portion of the plunger 13 is a 30 finger 22 which is adapted to close the contacts 21. Encircling the lower portion of the plunger 13 is a coil spring 23 having one end engaged with the guide 12 and its other end engaged with a 35 collar 24 on said plunger 13 for yieldingly urging said plunger downwardly.

It is thought that the operation of the device will be apparent from a consideration of the foregoing. When the lighter is resting on a support, the weight thereof maintains the plunger 13 in raised position against the tension of the coil spring 23, thus permitting the switch 20 to remain in its normally open position while the extinguisher 16 is engaged with the upper end of the wick 7. However, when the lighter is lifted from 40 the supporting surface, as when it is desired to light a cigar, cigarette or pipe, the plunger 13 is moved downwardly by the spring 23 in a manner to raise the extinguisher 16 to the position shown in dotted lines in Figure 3 of the drawings and 45 simultaneously close the switch 20 through the medium of the finger 22. When the switch 20 is closed current flows through the coil 8 to the electrode 10 and jumps to the upper end of the neck 6 of the container 5, thus igniting the wick 50 55

7. When the device is replaced on the supporting surface the plunger 13 is again raised against the tension of the spring 23, thus permitting the switch 20 to open while at the same time swinging the extinguisher 16 downwardly to operative position for extinguishing the flame on the wick 1. It may be well to here state that the casing 1 and the guide 12 are of insulating material.

It is believed that the many advantages of a 10 cigar lighter constructed in accordance with the present invention will be readily understood, and although a preferred embodiment of the invention is as illustrated and described, it is to be understood that changes in the details of construction and in the combination and arrangement of parts may be resorted to which will fall 15 within the scope of the invention as claimed.

What is claimed is:—

1. A lighter of the class described comprising a 20 casing having an opening in its bottom, a vertically arranged plunger slidably supported in the casing, with the lower end of the plunger passing through the opening, a spring tending to move the plunger downwardly to project the lower portion 25 thereof through the opening when the casing is lifted from a support, a liquid fuel containing tank in the casing having a neck projecting through the top of said casing, a wick passing through the neck, with its major portion 30 in the tank, an arm pivoted in the top of the casing and having an extinguisher part for engaging the upper end of the wick, when the arm is in lowered position, a link connecting the arm with the plunger for moving the arm to extinguishing position, when the plunger is in raised 35 position, and swinging the arm upwardly and outwardly away from the wick when the plunger is in lowered position, igniting means for the

upper end of the wick, an electric circuit for such means, including a switch, and means on the plunger and engageable with the switch for closing said switch when the plunger moves downwardly under the action of its spring, when the 5 casing is lifted from the support.

2. A lighter of the class described comprising a 10 casing having a flat bottom for resting on a support, and said bottom having a hole therein, a vertically arranged plunger slidably supported in the casing and having its lower end located in the hole, a spring for projecting the lower part of the plunger through the hole when the casing is lifted from a support, a tank containing liquid fuel in the upper part of the casing and provided 15 with a neck passing through the top of the casing, a wick in the tank having its upper end passing through the neck, a curved arm having its lower end pivoted in the top of the casing, with its other end forming an extinguisher for engaging the 20 upper end of the wick, when the arm is in lowered position, a link connected with the upper end of the plunger and with the lower end of the arm, outwardly of the pivotal point, whereby downward movement of the plunger will swing the arm away 25 from the neck and upward movement of the plunger will swing the arm into engagement with the neck, an electrode passing through the top of the casing, with its extremity arranged adjacent the upper end of the neck, said casing being 30 formed of non-conducting material, a circuit including the electrode and the tank, a switch in the circuit, and means for closing the switch upon downward movement of the plunger, the switch being opened when the plunger is in raised position. 35

OSCAR FAIRLESS.
